UNITED STATES PATENT OFFICE.

ALEXANDER MALM, OF NEW YORK, N. Y., ASSIGNOR TO T. W. & C. B. SHERIDAN, OF SAME PLACE.

PAPER-CUTTING MACHINE.

SPECIFICATION forming part of Letters Patent No. 434,285, dated August 12, 1890.

Application filed October 31, 1889. Serial No. 328,767. (No model.)

To all whom it may concern.

Be it known that I, ALEXANDER MALM, a citizen of the United States, residing at New York, in the county and State of New York, 5 have invented new and useful Improvements in Paper-Cutting Machines, of which the following is a specification.

This invention relates to certain improvements in paper-cutting machines of that class 10 in which both the knife and the paper-clamp are situated above the work-table and connected in such a manner that the pressure of the clamp upon the paper increases or diminishes with the resistance which is to be overcome by the knife.

The peculiar and novel construction of my paper-cutter is pointed out in the following specification and claims, and illustrated in the accompanying drawings, in which—

20 Figure 1 represents a side elevation. Fig. 2 is a front elevation. Fig. 3 is a horizontal section in the plane xx , Fig. 1. Fig. 4 is a similar section in the plane yy , Figs. 1 and 2. Fig. 5 is a transverse section in the plane zz , Fig. 2.

In the drawings, the letter A designates the frame which supports the working parts of my machine.

B is the work-table.

30 C is the knife, and D is the paper-clamp.

The knife C is firmly secured to a cross-head E, from which extends a stud into an oblique slot, Fig. 2, whereby a shear cut is imparted to the knife.

35 F F are two toothed segments, which are loosely mounted upon hollow studs G G, Fig. 3, secured in the standards of the frame A. On each of these segments is secured a stud a, which swivels in its bearing, and which

40 connects by a pivot b with the lower end of a connecting-rod c. The upper end of this connecting-rod is attached, by means of a pivot d, to a link e, which is connected to the cross-head E by means of a pivot f, Figs. 1 and 2. By

45 these means universal joints are formed at both ends of each of the connecting-rod c, so that the same can readily accommodate themselves to the compound movements of the knife and also to the movements of the seg- 50 ments.

By referring to Figs. 1 and 3, it will be seen that the swivel-studs a, which form the connections between the toothed segments F and the connecting-rods c, are near to the centers of motion of the segments; and, furthermore, 55 the toothed portions of said segments are much heavier than those portions which form the bearings for the swivel-studs a, so that said segments when left to follow their gravity assume the position shown in the drawings, 60 in which position they are arrested by stops g, Fig. 1, the weight of said segments being such that by their action the cross-head E, together with the knife C, is elevated above the table B, Figs. 1 and 5.

65 The paper-clamp D is firmly connected to slides h, which move in guideways i, Figs. 4 and 5, formed on the inner surfaces of the standards of the frame A, and the lower ends of which are connected by a traverse j. This traverse connects by links k with levers H, which swing on studs l in the standards of the frame A, and the loose ends of which are pivoted to arms m, which are loosely mounted on the traveling shaft I. This shaft extends loosely 70 through straps n n, which swing loosely on the driving-shaft J, and on the outer ends of said shaft I are firmly mounted pinions o o, which engage the toothed segments F F. The driving-shaft J extends loosely through the 80 hollow studs G G, Fig. 3, and on it are loosely mounted two pinions p p', between which is situated a clutch-sleeve K, which connects with the driving-shaft by a feather-key q, and which is so constructed that it can be thrown 85 in engagement either with the pinion p or with the pinion p'.

The pinion p is in gear with a cog-wheel L by means of an intermediate pinion p*, said cog-wheel L being firmly mounted on the 90 traveling shaft I, and the pinion p' meshes into a cog-wheel M, which is firmly mounted on the traveling shaft I. If the clutch-sleeve K is thrown in gear with the pinion p', the traveling shaft I is rotated in the direction of 95 arrow 1, Figs. 1 and 5, the segments F are turned in the direction of the arrows marked thereon in Figs. 1 and 5, and the knife C is caused to descend. If the clutch K is thrown in gear with the pinion p, the traveling shaft 100

I rotates in the direction opposite to the arrow 1 and the paper-clamp D is raised, so that a fresh pile of paper can be introduced.

The clutch-sleeve K can be moved by a hand-lever N, and it is moved automatically by one of the toothed segments F as soon as the knife C has completed its downward stroke. For this purpose the hand-lever N is connected by a rod r with a bell-crank lever O, from which 10 extends a tappet-rod P, Figs. 1 and 3, the free end of which is in such a position that it is acted upon by the segment F, and that the clutch-sleeve is moved at the moment the knife has completed its downward stroke. As 15 soon as the clutch-sleeve is thrown out of gear with the pinion p' the segments F return to their normal position and the knife is raised, and as the clutch-sleeve engages the pinion p the paper-clamp is raised and the paper 20 can be adjusted for the next cut.

What I claim as new, and desire to secure by Letters Patent, is—

1. In a paper-cutter, the combination, with the knife and with its cross-head, of toothed 25 segments mounted loosely on the driving-shaft, and rods extending from the cross-head to the segments and connected to the latter close to the shaft, whereby the gravity of the segments is enabled to raise the cross-head and 30 the knife, substantially as described.

2. The combination, with the frame A, cross-head E, and knife C, of the driving-shaft J, the segmental gears F, loosely mounted on the driving-shaft, the rods c, universally 35 jointed to the segmental gears and to the cross-head, a traveling shaft I, adapted to rotate in reverse directions and having two pinions meshing, respectively, with the segmental

gears, the paper-clamp D, connections between the traveling shaft and paper-clamp, and 40 clutch mechanism for imparting motion in reverse directions to the traveling shaft from the driving-shaft on which the segmental gears are loosely mounted, substantially as described.

3. The combination, with the cross-head E, the knife C, and clamp D of a paper-cutter, of the driving-shaft J, the segmental gears F, loosely mounted on the driving-shaft, the rods c, jointed to the segmental gears and to the 50 cross-head, the traveling shaft I, connected with the clamp and geared to the segmental gears, a clutch mechanism for imparting motion in reverse directions to the traveling shaft from the driving-shaft, and a clutch-operating lever having a tappet P, arranged 55 in the path of and operated by one of the segmental gears, substantially as described.

4. In a paper-cutter, the combination, with the knife C and the clamp D, of the driving-shaft J, the segments F, mounted loosely on the driving-shaft, the stops g for arresting the segments, the traveling shaft I, the pinions o, mounted on the traveling shaft and engaging the segments F, the pinions p p', mounted 65 loosely on the driving-shaft and geared in a reverse direction to the traveling shaft and the clutch-sleeve K, substantially as described.

In testimony whereof I have hereunto set my hand in the presence of two subscribing 70 witnesses.

ALEXANDER MALM.
